H. C. McCARTY.

SAFETY VALVE.

APPLICATION FILED FEB. 21, 1908.

910,711.

Patented Jan. 26, 1909.

UNITED STATES PATENT OFFICE.

HARRY C. McCARTY, OF WILLIAMSPORT, PENNSYLVANIA.

SAFETY-VALVE.

No. 910,711.

Specification of Letters Patent.

Patented Jan. 26, 1909.

Application filed February 21, 1908. Serial No. 417,145.

To all whom it may concern:

Be it known that I, HARRY C. McCARTY, a citizen of the United States of America, residing at Williamsport, Lycoming county, 5 State of Pennsylvania, have invented certain new and useful Improvements in Safety-Valves, of which the following is a specification.

The present invention relates to a safety 10 valve for steam boilers. It is of the kind commonly known as a "pop safety valve."

In valves heretofore made under the Coale 15 patents, No. 825,380, No. 855,431, and No. 657,086, it has been found that the large size valves have a tendency when discharged to rock in the case and strike the guides, producing an objectionable chattering sound and a destructive wear of the parts.

The present invention is designed to overcome 20 this defect and has successfully overcome it.

It consists of so constructing the valve as to give it a shallow concave outer surface and a convex inner surface. The cup form thus 25 given the valve causes it to protrude through its seat into the pressure chamber. A shallow step is located in the center of the outer surface of the valve which, when the valve protrudes through the seat into the pressure 30 chamber, will locate the foot of the spring-bearing block at the bottom of the valve cavity, and the pressure of the spring will be applied to the valve at a point on what may be called the pressure side of the seat. The 35

spring bearing block is so constructed as to leave a free open space between it and the surface of the valve which will not fill and be sealed by sediment. The surface of the 40 valve upon the pressure side by virtue of its shape is provided with a steam deflecting surface which causes the impact of escaping steam to be less effective in its tendency to tilt or rock the valve. The usual guides on each side of the valve are also provided. 45 These elements combine and coöperate to produce a valve which, even in large diameters, will not rock unduly or chatter in the case.

Various types of safety valve heretofore in 50 use have employed valves in which the pressure surface was curved, concave or convex. In some cases the valve protruded through the seat and the step of the spring bearing block was located at a point on the pressure 55 side of the seat. Guides have also been used on both sides of the valve and of various

shapes. But the defects of these various structures were found in the fact that the clearance between the spring bearing block and the valve was so small as to permit the 60 accumulation of sediment therein and thus seal the bearing block to the valve and destroy the independence of the valve. In some cases this difficulty was avoided by providing a considerable clearance between the 65 bearing block and the valve, but in those cases the step was at least as high as or beyond the seat on the exhaust side. In no structure of which I am aware has the combination ever been produced of a valve the 70 body of which protruded through the seat and having an inclined or convex surface upon the pressure side, a step located upon the pressure side of the seat, and the bearing block and valve so constructed in relation to 75 each other as to maintain a large clearance between them and the independence of the valve; with means for guiding the valve so as to keep it in its center position. This combination of features, all of which are in some 80 degree old, is a new combination never before made and which produces a new and improved result in safety valves, that is to say, it permits the construction of large sized valves which will operate positively and 85 without rocking or chattering under all kinds of conditions.

In the accompanying drawing, the figure 90 is a vertical central section of a safety valve embodying the invention.

The valve casing or chamber (1) is secured by the usual screw connection to the container (2) for fluid under pressure, to which the casing is connected by a suitable opening. The casing consists of a lower section (3) substantially cylindrical in form and having its axis in a vertical position. Its outer edge (4) is threaded upon the interior and it is provided upon its interior with a vertically projecting cylindrical flange, spaced from its 95 outer surface, upon the inner edge of which is the valve seat (8). Mounted upon the outer cylindrical edge, screwed into the internal thread (4) is an upper section of the casing (5), having its axis alined with that 100 of the lower section and provided with a reduced threaded portion (6) upon its exterior adapted to engage with the thread (4) upon the lower section. The upper end of the internal cylindrical flange of the lower section 105 is provided with a circular inclined valve seat (8). The upper section of the casing 110

above the valve seat is provided with a cylindrical guide 10, located over the valve seat and spaced from the outer wall of the casing (5), forming between the exterior wall of the casing (5) and the interior cylindrical guide (10) a circular chamber (11) which terminates at its lower extremity in an opening above the valve seat and at its upper extremity in a muffler (12), which will be hereafter termed 10 the "inner muffler". This muffler consists of the closed upper end of the chamber (11) perforated with holes (13) in its three sides. The upper section of the casing is also provided within the muffler with an integral vertical cylindrical extension (14) perforated at 15 its upper end and of less diameter than the inner muffler (12), forming with other members to be described an inclosure known as the spring chamber. The whole upper portion 20 of the casing including the inner muffler, the spring chamber, and the pressure screw of the spring which protrudes through the top of the spring casing (14) are inclosed by a dome or cap (15) which is perforated in its 25 top to form an external muffler, threaded at (16) to engage a corresponding threaded portion on the chamber (5) at a point just below the inner muffler (12). The upper end of this cap is provided with a central turret (17) 30 adapted to inclose the adjusting screw and lock nuts, and perforated in its vertical walls. 18 is a valve provided with a seat surface (19) normally resting on the seat (8) of the casing. The valve is concavo-convex and 35 protrudes through the valve seat, its lower or pressure surface being convex and its upper or exhaust surface concave. It is provided upon its upper or exhaust surface at its edge with a vertically projecting flange 40 (20), which is of an external diameter slightly less than the internal diameter of the cylindrical guide (10). These cylindrical surfaces coöperate to guide the valve in its motion. The valve is provided on its lower surface 45 with a hub guide (21), which enters and reciprocates in the stationary guide (9) which is within the lower section of the casing and on the pressure side of the valve seat. The under side of this valve is marked 22, and 50 as before described, is convex. It might be conical or concave so far as its function is concerned of deflecting the steam and reducing the effect of the impact of the steam upon the valve when escaping. The guiding surfaces (20 and 21) are slightly spaced from the corresponding bearing surfaces of the casing to allow for expanding and contracting of the parts due to variation of temperature. The curve of the under or pressure 55 surface of the valve extends from the seat surface toward the hub, because the effective action of the impact of escaping steam is greatest at or near the periphery of the valve. The top of the valve, as above stated, is con- 60 cave at 24, and in its center there is formed 65

a depression or cavity (25) which forms a step for the foot (28) of the bearing member (26). The lower surface (27) of the bearing member (26) is convex and is of less radius than the curve of the concavity of the valve, 70 leaving a free clearance space between the valve and the bearing member, while the foot (28) fits into and fills the step (25).

29 is the spring which rests at its lower end upon a recess (30) in the edge of the bearing 75 member (26), and at its upper edge in a recess (31) in an upper pressure block (32). The upper end of the spring casing (14) is perforated and provided with an internal thread (33).

(34) is the adjusting screw which is tapped 80 into the thread (33) and provided upon its lower end with a hemispherical surface which fits a socket or step in the upper bearing block (32).

35 is a head upon the upper end of the screw (34) and (36) a lock nut threaded on the screw, and when screwed down bearing upon the top of the spring casing (14) to 85 lock the screw in an adjusted position.

An important feature of the structure lies in the fact that the dome or cap (15) which forms the external muffler covers and incloses the adjusting screw as well as the inner muffler, and when removed for the adjustment of the screw (35) is so large and important a part of the structure that it is 90 not likely to be left off by those in charge of the apparatus.

Another advantage of this structure is 100 found in the fact that the screw is provided with a large strong head which permits the use of a large wrench and the positive adjustment of the screw with ease. The lock nut is located upon the screw between its 105 head and the top of the spring casing, and is not detached when the spring is adjusted. Hence the danger of its loss is avoided. The lock nut forms no portion of the casing and the diameter of the screw head is not limited 110 to that of the screw and may be made of any desired size and strength.

When the device is in operation the tension of the spring (29) is regulated by means of the screw (34) to yield to a predetermined 115 pressure on the under side of the valve. When this pressure is reached the valve lifts slightly, allowing steam to pass between the seat (8) and the seat surface (19) of the valve into the huddling chamber (37), and thence 120 out into the muffler. In this way the huddling chamber is filled with steam and the surface of the valve which is exposed to pressure is increased. The increased force 125 thereby applied to the valve raises it from its seat an appreciable amount, and steam escapes through the passages (11) to the inner muffler (12) and from thence to the external muffler (15). It will be noticed 130 that the cylindrical guide (20) of the valve

partially closes the spring chamber, so that the spring is not exposed to the principal part of the escaping steam. Whatever steam does enter the spring chamber escapes 5 through the holes in the top of the chamber and through the perforations of the turret (17). The independent motion of the valve is maintained by the form of the spring bearing block, its foot, and the corresponding 10 step in the surface of the valve; and the clogging is prevented by the free clearance between the bearing block and the valve.

The inclined deflecting surface (22) on the pressure side of the valve so controls the 15 effect of the escaping steam upon the valve that less irregularity of pressure and therefore less vibration and chattering of the valve results from this cause.

All of the elements above described 20 operate to produce a safety valve which, under the ordinary trying conditions of use, particularly on locomotives, will act promptly and smoothly, will muffle the escaping steam, will not discharge more steam than 25 the setting of the valve is designed to permit, will not chatter and consequently not wear, and will maintain the same effective and economical operation indefinitely.

Having thus described my invention, 30 what I claim and desire to secure by Letters Patent is:

1. In combination with a container for a fluid under pressure having an opening, a valve seat, a plurality of guiding members, 35 one internally and another externally disposed in regard to the container, the valve having a convex surface internally and a concave surface externally disposed, the latter extending through the seat, a bearing 40 member in the concavity mounted to rock freely in relation to the valve and a spring acting through the bearing member to press the valve against the seat.

2. In combination with a container for a 45 fluid under pressure having an opening, a valve seat adjacent the opening, a plurality of guiding members, one internally and another externally disposed in regard to the container, a valve having a convex surface 50 internally and a concave surface externally disposed, the latter extending through valve opening, a bearing member in the concavity having a convex surface of less radius than the concave surface of the valve, and a 55 spring acting through the bearing member to press the valve against the seat.

3. In combination with a container for a 60 fluid under pressure having an opening, a valve seat adjacent the opening, a plurality of guiding members, one internally and another externally disposed in regard to the container, a valve having a convex surface 65 internally and a concave surface externally disposed, the latter extending through the valve opening, a bearing member in the con-

cavity bearing against its upper surface, having a bearing surface which is convex and of less radius than the concave surface of the valve, mounted in the concavity to rock freely in relation to the valve, so that wedging and clogging of the parts by accumulation of rust flakes, or the like, is prevented and a spring acting through the bearing member to press the valve against the seat. 70

4. In combination with a container for 75 fluid under pressure having an opening, a valve seat adjacent the opening, a plurality of guiding members, one internally and another externally disposed in regard to the container, a valve having an outer surface 80 substantially concave and extending through the valve opening, a step in the concave surface, a bearing block in the concavity having a bearing surface substantially convex and of radius less than that of the concavity, a 85 foot on the bearing block engaging the step and a spring acting through the bearing block to press the valve against the seat.

5. In combination with a container for 90 fluid under pressure having an opening and a valve seat adjacent the opening, a plurality of guiding members, one internally and another externally disposed in regard to the container, a valve having an outer surface 95 substantially concave and extending through the valve opening, a deflecting surface on the pressure side of the valve terminating in the neighborhood of the valve opening, a block in the concavity having a bearing surface and of less radius than that of the concavity, and a spring acting through the block 100 to press the valve against the seat.

6. In a safety valve in combination with a casing having a seat and a guide, a valve having a seat surface and guide surface, an 105 inclined deflecting surface extending to a point adjacent the seat, the exhaust side of the valve being depressed to form a broad cavity extending through the seat, a bearing member in the cavity adapted to rock 110 freely in relation to the valve and a spring acting through the bearing member to press the valve against the seat.

7. In a safety valve in combination with a casing having a seat and guides on both the pressure and exhaust sides of the seat, a valve having a seat surface and guide surfaces, an inclined deflecting surface extending from one guide surface to a point adjacent the seat, the exhaust side of the valve 115 being depressed to form a broad cavity extending through the seat and having a central step, a bearing member in the cavity engaging the step and adapted to rock freely in relation to the valve and a spring acting 120 through the bearing member to press the valve against the seat.

8. In a safety valve in combination with a casing having a seat and a guide, the valve having a seat surface and a guide surface, 125

the exhaust side of the valve being depressed to form a broad cavity extending through the seat, a bearing member in the cavity adapted to rock freely in relation to the valve and a spring acting through the bearing member to press the valve against the seat.

Signed by me at Baltimore, Maryland, this 19th day of February, 1908.

HARRY C. McCARTY.
